US0D1054997S

(12) **United States Design Patent** (10) **Patent No.:** **US D1,054,997 S**
(45) **Date of Patent:** **** Dec. 24, 2024**

(54) **CONNECTOR**

(71) Applicant: **Japan Aviation Electronics Industry, Limited**, Tokyo (JP)

(72) Inventor: **Shoya Abe**, Tokyo (JP)

(73) Assignee: **Japan Aviation Electronics Industry, Limited**, Tokyo (JP)

(**) Term: **15 Years**

(21) Appl. No.: **29/861,611**

(22) Filed: **Dec. 1, 2022**

(30) **Foreign Application Priority Data**

Jun. 20, 2022 (JP) ..... 2022-013176 D

(51) **LOC (14) Cl.** **13-03**

(57) **CLAIM**

The ornamental design for a connector as shown and described.

DESCRIPTION

FIG. 1 is a front elevational view of a connector showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view showing a front, top and right side thereof;

FIG. 8 is a perspective view showing a rear, bottom and left side thereof;

FIG. 9 is a perspective view showing a front, right and bottom side thereof; and,

FIG. 10 is a perspective view showing a rear, left and top side thereof.

The broken line showing of the connector is for the purpose of illustrating portions of the article and forms no part of the claimed design.

1 Claim, 10 Drawing Sheets
